UNITED STATES PATENT OFFICE.

SHELDON E. JACKSON, OF WESTON, MICHIGAN.

STAY FOR WIRE FENCES.

SPECIFICATION forming part of Letters Patent No. 620,590, dated March 7, 1899.

Application filed July 14, 1897. Serial No. 644,496. (No model.)

To all whom it may concern:

Be it known that I, SHELDON E. JACKSON, a citizen of the United States, residing at Weston, in the county of Lenawee, State of Michigan, have invented certain new and useful Improvements in Stays for Wire Fences; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in wire stays or pickets for wire fences; and it consists in the construction and arrangement of parts hereinafter set forth, and pointed out particularly in the claim.

The object of the invention is to produce a wire stay or picket in which the construction is such as to enable it to be easily attached to the line-wires of a fence or a series of wires in a loom, so that the stay becomes coiled around the line-wires without bending said stay or line wires in the act of attaching and which becomes so fixed to the line-wires as to be securely retained in place, at the same time crimping the line-wires to form a slight bend therein and render the fence longitudinally elastic. This object is attained by the construction illustrated in the accompanying drawings, in which—

Figure 1 is a side elevation of a section of wire fence provided with my improved stay or picket. Fig. 2 is an enlarged elevation of one of the pickets before attaching to the fence. Fig. 3 is an enlarged elevation showing the opposed loops of the picket flattened upon the line-wire. Figs. 4, 5, and 6 illustrate the successive steps in the operation of attaching the stay to the line-wires. Fig. 7 is an enlarged detail in section, showing the kink in the line-wire caused by the flattening of the opposed loops of the stay-wire thereon.

In the construction of the fence the line-wires A are strung loosely, so that they extend between the supporting-posts A' without tension. The picket or stay wire B is composed of a single strand of wire of the proper size to afford the strength required and is provided with a series of reversed loops or bends a a', which stand in opposite directions

and between which the body-sections of the stay stand obliquely and connect the extremities of said loops. These series of reversed bends are located such distance apart on the stay-wire as to coincide with the longitudinal wires of the fence, of which there may be any number desired.

In the application of this improved stay to the line-wires of the fence said line-wires are slackened, and the stay or picket is attached thereto by winding or coiling the stay around each successive line-wire in the manner shown in Figs. 4, 5, and 6, in which the line-wire A is first dropped into the loop or bend a', the stay-wire extending at an acute angle to the line-wires. The lower or free end of the stay-wire is then raised, as shown in Fig. 5, and carried over the line-wire, as shown in Fig. 6, so that the line-wire passes through both loops a a'. Each succeeding line-wire is engaged by the stay-wire in the same manner. The stay-wire when all its loops have been engaged to the line-wire will stand at a slant, but may be straightened to a vertical position and moved to any desired point and secured by flattening said loops or coils onto the line-wire, as shown in Figs. 1 and 3. The operation of flattening the loops on the line-wire causes a kink in the line-wire at that point, as shown in Fig. 7, whereby the stay is more securely held in position and the line-wire is prevented from being drawn perfectly straight, thus rendering the line-wire longitudinally elastic to compensate for expansion and contraction and adding lateral flexibility to the fence.

By means of this improved stay a fence of great strength may be quickly and cheaply constructed. The stays, being first provided with the series of right-angle bends a a' at the requisite distance apart, may be quickly and easily attached to the line-wires without bending said stays or wires, and when properly attached to the line-wires, as before described, the stay becomes coiled around each succeeding wire and may be straightened to a vertical position or moved to any point desired, after which suitable tension is placed upon the line-wires and the fence is complete.

Having thus fully set forth my invention, what I claim as my invention, and desire to secure by Letters Patent, is—

In a fence, the combination with the line-wires, of the stay consisting of a wire provided with a series of reverse return-bends between which the intervening sections of the body of the stay extend obliquely and unite the extremities of said bends, which extremities are open and free of access, said intervening sections being of such length that the inner arc of the opposed bends embraces the

line-wires and forms a single wrap there-around.

In testimony whereof I affix my signature in presence of two witnesses.

SHELDON E. JACKSON.
